Julius Meyer.

Julius Meyer, of Cincinnati, O.
Letters Patent No. 945. Dated Sept: 29, 1857.

The schedule referred to in these Letters Patent, and making part of the same.

To all whom it may concern:

Be it known that I, Julius Meyer, of the city of Cincinnati, in the County of Hamilton, and State of Ohio, have invented or produced a new design for a stand for Shovel & Tongs, and I do hereby declare, that the shell work represented in the annexed drawing is a full and exact description of the same.

What I claim and desire to secure by Letters Patent, is the new design for a Shovel and Tongs Stand, consisting in the ornamental Figures set forth in the accompanying drawings.
